COMPRESSOR SYSTEM

Humphrey F. Parker, Detroit, Mich.

Application May 21, 1938, Serial No. 209,181

2 Claims. (Cl. 184—6)

The present invention relates to compressor systems, and in particular provides an improved compressor system for supplying air or other fluid under pressure for the operation of brakes, door openers, or the like on automotive vehicles such as buses and trucks.

The principal objects of the present invention are to provide a system of the above generally indicated character, which is adapted to remove from the delivered air or other fluid the non-gaseous impurities such as excess lubricating oil and solid or liquid decomposition products thereof, thereby freeing the collecting reservoirs of objectionable accumulations of such matter and preventing deposits thereof on valves and other parts of the operating mechanism; to provide a system which makes practicable the use of simpler types of compressors, such as the rotary type, than have heretofore been found to be practicable; and to provide such a system which reduces the delivery temperature of the air or other compressed fluid, by introducing into the air or other fluid a quantity of oil or the like which absorbs a portion of the heat of compression.

Further objects of the present invention are to provide a system of the above generally indicated type, characterized in that oil for lubricating and for sealing the clearance spaces in the compressor is supplied thereto from the lubricating system of the associated vehicle engine; to provide such a system in which the excess of the oil supplied to the compressor is returned therefrom to the vehicle oiling system; to provide such a system in which means are provided to separate the oil from the compressed fluid and in which the separated oil is returned to the supply system; to provide such a system including means to return to the engine lubricating system all but a predetermined quantity of the oil supplied to the compressor, thereby insuring the maintenance of a proper oil supply in the engine system; and to provide such a system embodying improvements in the construction and arrangement of the parts thereof.

With the above as well as other objects in view, which appear in the following description and in the appended claims, preferred but illustrative embodiments of the invention are shown in the accompanying drawings, throughout the several views of which corresponding reference characters are used to designate corresponding parts and in which:

Figure 1 is a general view in elevation, partly in section, of a preferred embodiment of the invention;

Figure 2 is a view in bottom plan of the improved compressor of the present invention;

Figure 3 is a view in vertical longitudinal section, taken along the line 3—3 of Figure 2;

Figure 4 is a view in vertical transverse section, taken along the line 4—4 of Figure 2;

Figure 5 is a view in vertical longitudinal section, taken along the line 5—5 of Figure 2;

Figure 6 is a view in horizontal section, taken along the line 6—6 of Figure 3;

Figure 7 is a view in vertical transverse section, taken along the line 7—7 of Figure 2;

Figure 8 is a view in vertical section, taken along the line 8—8 of Figure 3; and

Figure 9 is a fragmentary view of a modified embodiment of the invention.

It will be appreciated from a complete understanding of the invention that the improvements thereof may be embodied in compressor systems of widely differing types, and adapted for widely differing applications. In the specific forms illustrated, however, the improvements of the invention are particularly adapted for use in connection with automotive vehicle compressor systems, it being understood that in such systems the compressed air or other fluid may be utilized to operate the brakes, doors, and other mechanism associated with the vehicle.

Referring to the drawings, the improved compressor 10 of the present invention is supported at the side of an internal combustion engine 12 by means of the bracket 14. The compressor 10 is believed to be of itself of novel form and is of the gear type. It will be understood, however, that in its broader aspects, the invention is applicable to other forms of compressors, such as radial vane compressors and also such as reciprocating compressors. It will be appreciated that in the use of rotary compressors of the illustrated gear type, it is desirable to supply oil thereto both for the purpose of lubricating the compressor bearings and for the purpose of sealing the clearance spaces around the gear teeth, to prevent leakage losses which would otherwise occur due to normal manufacturing tolerances. The arrangement of the present invention is such that oil is supplied to the compressor 10 by the engine oil pump for both of the just mentioned purposes.

The shaft 16 of the compressor 10 is driven, through the flexible coupling 18, from any suitable moving part of the engine, such as the shaft of the generator (not shown). In a broader sense, it will be appreciated that the compressor may be driven in any other suitable way, such as by means of a belt and pulley. It is preferred that the compressor 10 be arranged for continuous operation whenever the vehicle driving engine is in operation, thus dispensing with clutches, but making advisable the provision of unloader or relief valve mechanism which is described below.

The lubricating oil pump 20 of engine 12 is driven from the engine crankshaft 22 by means of the usual helical gears 24 and 26. Oil is taken from the engine sump 28 through the inlet 30 of pump 20, and is delivered under pressure thereby to the pump outlet 32. Passage 34 communicates directly with the outlet 32, and transmits the oil

to a longitudinal header 36, from whence it is distributed to the main bearings and other parts of the engine to be lubricated. The header 36 is tapped into by a compressor oil line 38, the other end whereof is suitably connected into the compressor inlet 40, as most clearly appears in Figures 1 and 4. Preferably and as illustrated, the compressor inlet 40 is provided with a metering orifice 42, which serves to limit the amount of the oil delivered to the compressor to a suitable quantity.

The quantity of oil delivered to the compressor 10 through the metering orifice 42 is preferably considerably in excess of that required for lubrication, and may, for example, be of such an order that the weight of the delivered oil equals or somewhat exceeds the weight of the air or other fluid taken into the compressor. The excess of such oil, over and above what is required for lubricating purposes, is utilized in the practice of the present invention for the purpose of sealing the clearance spaces within the compressor and also for suitably reducing the temperature of the compressed air or other fluid. As is described more in detail hereinafter, the just mentioned excess oil is separated from the compressed air or other fluid and all such oil in excess of a predetermined quantity is returned to the supply system.

Referring further to the drawings and particularly to Figures 3 and 4, oil delivered through the metering orifice 42 strikes the teeth of the gears 44 and 46, and is carried around in the spaces between the gear teeth, along with air inducted through a usual air filter 48, air line 50, and compressor air inlet 52. The air is compressed by the action of the gears 44 and 46 in a well known manner, and is discharged, along with the entrained oil, through an outlet 54, which as most clearly appears in Figures 3 and 7, opens directly into a separating chamber 56.

The separating chamber 56, which is formed integrally with the gear chamber, is of relatively large area, and is filled or substantially filled with a material such as steel or copper wool. As shown, the separator 56 is provided with suitable baffles 58 and 60 to cause the air to follow a tortuous path therethrough, as is generally indicated by the arrows in Figure 6, from the inlet 54, around the baffles 58 and 60. Due to their inertia, the liquid oil particles adhere to and collect upon the surface of the steel or copper turnings. The oil film thus deposited gradually forms into drops which are too heavy to be carried forward by the low velocity air stream, and such drops, accordingly, fall by gravity and are collected within a sump 62 formed at the bottom of the separator 56. The air, thus freed of its entrained oil, passes out of the separator 56 through a passage 64 (Figures 5 and 7).

The compressed air or other fluid, delivered from the separator 56 through the passage 64, flows through the communicating passages 63 and 65 past a spring loaded non-return valve 66 into a chamber space 68. As clearly appears in Figure 6, the chamber space 68 communicates directly with the compressor delivery pipe 72. It will be understood that the delivery pipe 72 may lead directly to a suitable collecting reservoir (not shown), from whence the air or other fluid may be drawn for the operation of brakes and other equipment.

The oil collects in sump 62 until its level rises sufficiently to lift the float 74. Float 74 in turn lifts valve 76, which places a passage 77 leading

from sump 62 in communication with an outlet port 78. The outlet port 78 leads through the oil return pipes 80 and 82 back to the engine sump.

It will be noted that the return pipe 82 is provided with an additional branch 84 which is connected into a short passage 85 which in turn opens into the bottom of the compressor air intake 52 (Figure 4). The purpose of this branch connection is to permit a direct return of the oil to the engine sump in the event of the stoppage of the compressor while the engine 12 is in operation. While this eventuality is very remote, it is preferred that it be provided for in certain cases, for example when the drive is by means of a belt and pulley. The branch line 84 remains open during the time that the compressor 10 is in operation. During such operation, however, the great majority of the oil delivered from the metering orifice 42 directly impinges upon the gear teeth and is thereby carried around into the compressor as described above.

As previously mentioned, it is preferred to provide the compressor with suitable unloader or relief valve mechanism. Referring particularly to Figure 5, a passage 86 leads to the bottom of the previously mentioned chamber space 68 into a chamber space 88, which is thus subject to the fluid pressure in the space 68 and in the delivery line 72. The just mentioned pressure within the chamber 88 acts upon a metal bellows 90, and is resisted by a spring 92 and the air pressure acting upon a valve 94, the push rod 95 whereof rests against the inner member 97 forming the closed end of the bellows 90. When the pressure upon the bellows exceeds the just mentioned opposing forces, the valve 94 is forced open, permitting air to escape from the separator 56, and thence through the passage 63 and 96 directly into the compressor air inlet 52. The return valve 66, however, which is maintained in its closed position under the just mentioned conditions by its associated spring 67, serves to prevent a flow of air from the storage reservoir and line 72 through the relief passage 96. In consequence, a high pressure is maintained in the storage reservoir although the delivery side of the compressor and separator are substantially relieved of pressure. Continued operation of the compressor causes the usual circulation of air therethrough, but because of the absence of back pressure, the engine is relieved of the load of compression.

It will be noted that once the valve 94 is forced open, it is relieved of the pressure on its upper face, so that the pressure on the metal bellows 90 exceeds the resistance of the spring 92 by a considerable margin. When the pressure within the reservoir falls, due for example to the application of the brakes or other equipment to be operated thereby, the pressure on the bellows is reduced below such margin, rendering the bellows 90 unable to balance the resistance of the spring 92. Valve 94 thereupon moves to the closed position, and pressure is again built up upon the delivery side of the compressor until such pressure equals that on the reservoir side of check valve 66, at which time valve 66 again opens permitting the delivery of the compressed air to the storage reservoir.

It will be noted that the compressor 10 is illustrated as comprising two companion sets of gears 44 and 46 and 98 and 100. The provision of these two sets of gears provides two stages of compression, whereby losses in volumetric efficiency due to clearance spaces between the gear

teeth are materially reduced. In the illustrated arrangement, two separate chambers for the sets of gears 44 and 46, and 98 and 100 respectively, are provided within the housing by a partition defined by spaced wall members 105 and 107. The air delivered into the chamber associated with the first pair of gears 44 and 46, through the inlet 52, is carried around by these gears and passes into the space 103 between the two partitions through an opening 101 formed in the partition 105. The air passes along the just mentioned space, to the inlet side of the compressor, and is admitted to the inlet side of the gears 98 and 100 through an opening 108 formed in the partition 107. After being carried around in the spaces between the teeth of the gears 98 and 100, the air passes into the separator 56, through the previously mentioned outlet 54, which is formed in the inner wall of the gear housing. It will be appreciated that the oil delivered into the compressor through the metering nozzle 42, in part adheres to the teeth of the gears 44 and 46, thereby sealing the clearance spaces therebetween; in part is carried around by the air and adheres to the teeth of the gears 98 and 100, thus correspondingly sealing the clearance spaces therebetween; and in part is carried by the air into the separating chamber 56, following which it is recollected in the previously described manner.

In the present instance, the lubrication of the compressor bearings 104, 106, 108, and 110 is adequately taken care of by oil from the film which occupies the clearance spaces between the ends of the gears and the casing. It will be understood, of course, that in the broader aspects of the invention, full engine oil pressure may be supplied to the just mentioned bearings by providing a suitable passage leading from the oil intake 48.

It will be appreciated that a substantial part of the heat of compression is transferred to the oil which is entrained with the air being compressed, so that the air is delivered to the storage reservoir (not shown) at a substantially lower temperature than would otherwise be the case. As will be further understood, the actual degree to which the temperature of the air is reduced, depends upon the relative weights of the air and the oil.

The absorption by the oil of part of the heat of compression of the air necessarily raises the temperature of this oil to a value higher than the temperature at which the oil may be expected to enter the compressor inlet 40. However, in the embodiment described above, the recollected oil, in excess of a predetermined quantity thereof, is returned directly from the sump 82 to the engine sump, which latter sump is occupied by a relatively large body of oil and may be expected to be maintained at a temperature substantially lower than the initial temperature of the recollected oil. Accordingly, the present arrangement provides for the cooling of the recollected oil before it is again circulated through the compressor.

In certain instances, where the just mentioned cooling effect is not of substantial importance, it has been found that an economy in the amount of oil lines required may be effected by the arrangement shown in Figure 9, in which only a single oil line is required between the engine and the compressor.

In Fig. 9, the oil is delivered as in the pre-

viously described embodiment to the compressor from the vehicle oil pump 20, through the line 38a and the compressor oil inlet 40a. In this instance, however, the compressor oil outlet 78a, instead of being connected to a line leading to the oil engine pump, is connected to a line 112 which is tapped into the supply line 38a.

It will be appreciated that the oil pressure within the line 38a, as developed by the pump 20, is of a moderate value of the order, for example, of about 30 pounds per square inch, whereas the pressure existing within the compressor separator, may be expected to be of the order 100 pounds per square inch. When the float controlled valve associated with the compressor separator opens, the oil in the bottom of the separator pump is discharged into the line 112 at the just mentioned relatively high separator pressure, against the relatively low supply pressure in the line 38a. Under normal conditions, accordingly, the oil discharged through the oil outlet 78a re-circulates directly into the compressor oil inlet 40a. Any tendency towards a reduction in the normal quantity of oil in the local circuit including the line 112 and the compressor 10 is met by an additional supply of oil from the pump 20 through the line 38a, thus bringing the quantity to the normal expected value. On the other hand, any tendency for the quantity of oil in the just mentioned local circuit to exceed a predetermined normal, is overcome by the ability of the superior pressure in line 112 to force oil back through the line 38a into the engine header 36, it being understood, of course, that the back pressure at the compressor inlet metering orifice is substantially equal to the pressure developed by the pump 20.

Except in the respect noted above, the embodiment of Figure 9 may and preferably does correspond in all respects to the embodiment shown in Figures 1 through 8, and this relation is indicated by the use of corresponding reference characters, with the subscript *a*.

Although only two specific embodiments of the invention have been disclosed in detail, it will be appreciated that various other modifications may be made in the form, number and arrangement of the parts within the spirit and scope of the invention.

What is claimed is:

1. The combination of an engine, a compressor associated with said engine, an oil reservoir in said engine constituting a source of lubricant therefor, means including a pump and a fluid line for delivering oil from said reservoir to said compressor, means for controlling the quantity of the oil so delivered, and means associated with said compressor for separating the oil entrained with the compressed fluid from said fluid at a pressure in excess of that developed by said pump and for returning oil in excess of a predetermined quantity from said last named means to said fluid line.

2. The combination of an engine having a rotating part, a rotary compressor driven from said part, a lubricating system for said engine, means for delivering oil from said system to the inlet side of said compressor to lubricate and seal the same, an eliminator for separating the oil entrained with the compressed fluid from said fluid at a pressure above atmospheric, and means for returning said separated oil to said engine lubricating system.

HUMPHREY F. PARKER.
